UNITED STATES PATENT OFFICE.

HARRY D. FINBERG, OF ROXBURY, AND SAMUEL S. LEVY, OF DORCHESTER, MASSACHUSETTS.

HEATER.

1,355,220.

Specification of Letters Patent. Patented Oct. 12, 1920.

Application filed December 4, 1916. Serial No. 134,998.

To all whom it may concern:

Be it known that we, HARRY D. FINBERG, a citizen of the United States, residing at Roxbury, in the county of Suffolk and State 5 of Massachusetts, and SAMUEL S. LEVY, a subject of the Czar of Russia, residing at Dorchester, in the county of Suffolk and State of Massachusetts, are the joint inventors of a new and useful Improvement 10 in Heaters, of which the following is a specification, like numerals referring to like parts throughout the several views of the drawing.

This invention relates to heaters and pertains more particularly to water heaters 15 applicable to gas ranges, oil ranges, electric ranges and the like and adapted to be interposed between the flame or heated area and a cooking or a culinary vessel.

20 In carrying out the objects of our invention, the embodiment thereof in its preferred form, includes a system of tubular water containing members distributed in an efficient and effective manner about the 25 heated area of a gas or other flame preferably combined with a casing adapted in its construction to present units thereof or a unit construction.

In order to illustrate said invention, we 30 have shown in the accompanying drawing one embodiment thereof wherein:

Figure 1 is a plan view of a heater and casing of the invention.

Fig. 2 is a central longitudinal section on 35 Fig. 1.

Fig. 3 is a similar section illustrating a modified form of casing.

Fig. 4 is a transverse section on line 4—4 of Fig. 2.

40 Fig. 5 is a similar transverse section on line 5—5 of Fig. 3.

Fig. 6 is a detail in perspective of a heater shield.

Fig. 7 is a transverse section of said 45 tail.

The terms employed herein are used in the generic and descriptive sense and therefore are not intended primarily as terms of limitation.

50 In the drawing, 10 represents a rectangular box like frame provided with the depending side members 11 and end members 12 and 13 each having therethrough a series of arched openings 15 or other openings adapted to permit of the circulation of

air beneath the casing. The top face 16 of the said casing may be integral with the aforesaid members as in Figs. 3 and 5, or as in Figs. 1, 2, and 4, the upper portion of the said casing may be provided with a flange 60 17 upon which rests or upon which is secured the top or hot plate 18. In the case of the latter construction, the said hot plate may be provided at one end with a pair of lugs 19 adapted to extend beneath and embrace the lower face of the flange 17 and the opposite end of said plate may be provided with one or more latches 20 adapted to be moved into and out of position beneath the flange 17. 65

This latter construction allows for the removal of the top or hot plate 18 for the purpose of permitting an inspection, cleaning, or repairing of the heater or the tubular members hereinafter described. 70

Whether the said hot plate 18 is integral with the casing or detachable therefrom it is provided with circular openings 22 surrounding which are depressed flanges 23 adapted to receive thereon a cover 24 of any 80 suitable or preferred type. 75

Said covers may consist of the usual type of plain stove cover 24 or any suitable modification thereof consisting, for example, of a plurality of concentric ring like members 85 one nested within the other each adapted to present an opening of a different diameter above which opening or within which may be set a cooking vessel or the like.

In its preferred embodiment, the heater 90 and casing consists of a unit like construction or any multiple thereof adapted to extend over or across two or more burners of a gas or other range. In other words, the heater is adapted in its dimensions to extend 95 across two or three burners of a range of the type mentioned. If additional heaters or heating surfaces are required another heater of similar type is placed over and across adjacent burners of said range. The 100 casing is preferably provided with as many covers and cover holes as desired or the same may be equivalent to the number of burners across which the heater is placed. 105

Within the casing 10, is located the heater 110 proper consisting of a plurality of tubular coils or the like, adapted in their arrangement and construction to present a continuous thermal circulation system, and adapted in its arrangement to conserve the thermal

units supplied thereto and impart same as near equally as possible to all portions of said heater.

For this purpose we provide an inlet pipe 25 adapted to be coupled to the bottom level of a hot water storage tank or the like for domestic purposes from which said inlet 25 passes through an opening through the end member 12 and extends to a point adjacent to the end member 13. Near the end member 13 the said pipe is curved at a wide radius to bring the same close to and paralleling the side member 11 to form the coil 26. The coil 26 is at a slightly higher level than the inlet pipe 25 and extends to the end member 12 where it is curved in a wide radius to form a coil 27 extending along and parallel to the side member 11 opposite the location of coil 26. Near the end member 13 the coil 27 is curved in a wide radius and joins the coil 28. The coil 27 is at a slightly higher level than the coil 26 and the coil 28 is at a still higher level than the preceding coils until it reaches the end member 12 where it is curved and joins with the coil 29 at a still higher level. It will now be noticed that the coils 28 and 29 are interposed between the coils 26 and 27 in their respective order and are nearer the longitudinal center of the heater. The coil 29 parallels the coil 27 to a point near the end member 13 where it is curved to join the outlet coil 30 at a still higher level than any of the preceding coils and close to and parallel to the inlet 25. Said outlet passes through an opening in the end member 12 where it is coupled to the aforesaid hot water storage tank at a much higher level than the inlet 25. Thus the incoming water flows through the inlet pipe 25 along the center of the flame heated area from thence it is branched out to the sides of the heater farthest removed from the inlet from which its succeeding convolutions or coils approach the center of said flame heated area at continuing higher levels, after which the heated water is conveyed back to the hot water storage tank along the center of the heated area and in a position parallel and next adjacent to the inlet.

Therefore, the flame and heat about the heated area of a gas range are deflected alternately by the heater coils to enlarge as far as possible the actual heating area. The respective positions of the said water containing coils also tends to radiate the heat from adjacent coils to the coils containing the water at a lower temperature and therefore it is a principle of our invention to apply the heat as uniformly as possible throughout the entire extent of the said coils.

The coils being of the thinnest tubing necessary to withstand the water pressure, take up the heat units very rapidly, and

with the wide radius of the bends between adjacent coils permit of rapid and unobstructed circulation. By means of coils of this type, leaking joints and couplings are dispensed with so that a much stronger coil structure is obtained. Also the wide sweeping radius at which the coils are joined one to the other best enables the metal tubing to be bent without undue straining or thinning of the metal along the outer portion of the curves and is best adapted to withstand the expansion of the coils or any tendency to straighten.

In order to support the respective coils, we provide a plurality of brackets 32 extending from near one side member 11 to a point near the other and provided with saddle portions 33 the latter being so arranged or spaced as to maintain the different coils in their respective and relative positions both horizontally and vertically.

The said brackets 32 may be integral with the side members 11 as in Fig. 4 or may be provided with lugs 34 bolted at 35 to the hot plate 18 as in Fig. 5. Any desired number of said brackets may be employed at positions between the cover holes 22.

If the hot plate 18 is integral with the frame 10, then it will be preferable to employ the means of fastening consisting of the lug 34. On the other hand, if the removable hot plate is employed the said bracket 32 may be integral with the side members 11.

Integral with the removable hot plate 18 is a corresponding bracket 38 having saddle portions 39 corresponding with the saddle portions of its co-acting bracket 32, in order that when all the members hereinbefore mentioned are assembled, the coils being located within the said saddle portions will be retained therein or held thereto preventing displacement of the latter from any cause whatsoever. In Fig. 5 the bracket 38 is separate and bolted at 40 to the bracket 32.

While the brackets 32 may correspond in shape to the transverse contour of the respective coils and thereby permit for as much circulation of air within the casing 10 as may be possible nevertheless, it is desirable and preferable that the respective brackets shall be as open as possible to permit of free circulation of heat from the heated area. Therefore between the saddle portions 33 and 39, the said brackets are provided with openings 41 and in addition other openings 42 may be had through the said brackets enabling the air and the heat to circulate freely from one portion of the casing 10 to another.

Interposed between the heating means, flame, or the like and each of the heater coils is a guard, deflector, or the like 45 of trough like circular construction bowed or bent longitudinally or to an angular form from end to end thereof as illustrated in

- Fig. 6. Therefore the center or central portion of said guard or deflector 45 abuts the coil to which it may be secured by means of the ears 46 crimped or bent about the coil.
- 5 Therefore the ends of the said guard are removed or separated from the coils to permit of the circulation of heat and air about the coil. In this manner, the flame is prevented from coming into direct contact with
- 10 any of the coils of the heater permitting, at the same time, of the free circulation of heat throughout the extent of said coils. Said guards furnish means for taking up heat units applied thereto during the operation
- 15 of the heater and re-radiating the same both to the coils and a cooking vessel located above a cover hole 22. When the gas or other flame is extinguished the said guards being in a heated state, will like the adjoining
- 20 pipes re-radiate their heat to the pipes and assist in maintaining a circulation of the water for a period longer than the operation of the said flame.

From the entire construction, it will be seen that every advantage is taken to confine the heat units to the coils and to the cover plates, thereby taking advantage of a large loss heretofore dissipated and overcomes in a very large measure the uneconomical operation of gas or other ranges at present employed.

The entire casing 10 may be secured to the range or the like in any suitable or preferred manner. For example, herein illustrated in Fig. 1, are lugs 50 at each corner of the frame 10 through which lugs any suitable or preferred fastening may be inserted to clamp the frame 10 to the range in position above the burners 51 or other heating medium. Likewise it will be seen that in the employment of a unit construction as herein set forth that no alterations, reconstructions or adjustments of the present types of ranges are necessary in order 45 to adapt the invention to such range.

In its application, the invention is adapted not only to heat water in a storage tank, or the like, for future use, but is also adapted for all other culinary purposes to which a 50 gas or other range may be utilized. Cooking utensils of every kind and description may be placed above the cover holes 22 with or without removal thereof and said utensils will be heated in the same manner as heretofore. On the other hand, by employment of the coil, the heat is not only deflected and distributed evenly throughout the heater but heat units heretofore lost by the use of an

open flame or the like is utilized to transfer said heat losses to water to be stored for future use.

The openings 15 in the frame 10 permit of sufficient circulation of oxygen to allow a gas, or the like, to burn with a clear blue flame which is directed upwardly and spread out over a much larger area than is the case with the open flame.

By constructing the casing with a removable hot plate, access can be had at all times to the coil and to the interior of said casing for the purpose of cleaning the same or making any repairs that may be necessary from time to time.

We have described one embodiment of our invention; but it is to be understood that the latter is not essentially limited to the specific details of construction and organization of said embodiment, since the same may be varied without departing from the proper scope of the claims.

We claim—

1. In a heater of the character described, a casing, a detachable hot plate with cover holes, a tubular coil within said casing provided with a rising incline to each advancing section of the coil throughout the entire length thereof, brackets on said casing provided with saddle portions positioned at different planes for supporting said coil, and coöperating brackets on said hot plate also provided with corresponding saddle portions for maintaining said inclined coil in position within the saddle portions in the first mentioned brackets.

2. In a heater, a coil and a plurality of deflectors on said coil, each of said deflectors having a contracted central portion and flared end portions and means for attaching said deflectors in position on said coil.

3. In a heater, a coil and a plurality of trough shaped deflectors on said coil, each of said deflectors having a contracted central portion and flared end portions, and means for attaching said deflectors to said coil and in spaced relation thereto.

4. A water heater of the class described, comprising a coil having a centrally arranged inlet pipe thence bent to form the outer convolution of the coil then gradually decreasing to the center thereof to form the outlet from said coil, said coil being a rising incline thereto to each advancing section thereof, starting at said inlet and continuing throughout the entire length of the coil.
